LIQUID DISPENSER

Zenon Fleury Monteiro, São Paulo, Brazil

Application November 29, 1949, Serial No. 130,042

2 Claims. (Cl. 4—228)

1

The present invention relates generally to the feeding or dispensing of small quantities of liquids into a stream or into a body of water. The present invention is particularly applicable to conditions where a relatively large receptacle is repeatedly filled with water, or any other liquid, and discharged, and where it is desired to provide this body of water with a small amount of another liquid, such as a disinfectant or any other chemical.

It is the object of this invention to provide a simple and rugged device which may be employed under these conditions of use so that it will automatically feed a small amount of chemical into the larger body of liquid.

In order to accomplish the above purposes, the present invention provides a small receptacle containing the desired chemical in dissolved or liquid state, which is associated with a larger container through which the larger body or stream of water flows. In the preferred form of the invention, this smaller receptacle is placed within and at the bottom of the larger container. It is therefore another object of the present invention to provide a system of this type in which the filling of water in the larger receptacle serves to store up energy within the small receptacle, which is subsequently employed for the discharge of a measured amount of liquid from the small receptacle.

A still further object of the invention is to provide a system of the type described which operates to discharge a measured amount of chemical liquid into the larger body of water as the same is being discharged from the larger receptacle.

Other objects and advantages of the present invention will be more clearly understood from the following specification and the accompanying drawings; the same serving to describe an illustrative embodiment of the invention, it being understood that variations thereof falling within the scope of the appended claims will be apparent to persons skilled in the art.

In the drawings, Fig. 1 illustrates one form of the invention and shows the larger receptacle empty. Figs. 2 and 3 show the invention in the process of filling the larger receptacle. Fig. 4 shows the larger receptacle filled with water to the customary level. Fig. 5 is an isometric view of a different form of the smaller receptacle. Fig. 6 is a sectional view of the same receptacle taken on line 6—6 of Fig. 5. Fig. 7 is an enlarged sectional view showing the smaller receptacle disposed exteriorly of the larger one.

5 In the specific form of the invention illustrated in the accompanying drawings, a small receptacle containing any desired chemical in relatively highly concentrated condition is disposed within and preferably on the bottom of a larger receptacle, which, in the course of use, is repeatedly filled with water and discharged. The present invention is applicable to such a system where the repeated filling and discharging of the larger 10 receptacle may be at regular intervals or irregular intervals. More particularly, the present invention has specific application in the supply of a disinfectant to the water employed in water closet flush boxes. It will be understood, however, that the invention is applicable to many other systems.

15 In the present invention, the small receptacle is substantially filled with the desired liquid and during the filling operation of the larger receptacle, the pressure of the air entrapped at the top of the small receptacle is increased, and this increase in pressure serves during the discharge of the larger receptacle to expel a small quantity of its contents into the larger receptacle.

20 Referring more specifically to the drawings, 10 or 10' shows a larger receptacle which may be periodically filled with water or any other suitable liquid entering through an inlet 11, and the same is periodically discharged through a bottom outlet 12. In systems of this type, the inlet valve 13 and outlet valve 14 are controlled by any suitable means well-known in the art. In these well-known systems, the valve 13 may be float controlled or is otherwise responsive to the level of the liquid in the receptacle or tank 10. The outlet valve 14 in the system is commonly operated to open position by a manual or other device, and does not close again until after the box or tank 10 is substantially emptied.

25 40 The small receptacle 20 is closed at the top, as shown in Figs. 1 to 4, and is provided with a lateral opening 21. In the form of the invention shown in Figs. 1 to 4, this lateral opening 21 receives a stopper 22 made of any suitable material, such as cork or rubber or the like. The stopper 22 is provided with a passage 23, which receives the bent tube 24 at one end and the preferably relatively large outlet having downwardly and outwardly divergent walls forming the bell mouth 25 at the other end. The cross-sectional area of the bell mouth 25 should be roughly from 30 to 40 times the cross-sectional area of the tube 24.

50 45 The outlet opening 21 of the receptacle 20 should preferably be quite close to the top of the

receptacle. The lower end of the tube 24 should extend downwardly and approach the bottom of the receptacle, as shown. The bell mouth 25 may extend down to the same level as the lower end of the tube 24, but should not extend below it. The open end of the bell mouth 25 should preferably be spaced substantially from the bottom of the flush tank 10.

At the start, the level of the liquid within the small receptacle 20 is roughly as indicated in the drawings, and is such as to maintain the tube 24 filled without causing the liquid to flow through the tube and outwardly therefrom. It will be understood that depending upon the inner diameter of tube 24 and the magnitude of capillary forces involved, the level of the liquid in the receptacle 20 may be substantially above the upper end of the tube 24.

In the condition of the apparatus shown in Fig. 1, the receptacle 20 is disposed at the bottom of the empty flush tank 10. The tube 24 is practically filled with the chemical liquid and the bell mouth 25 is empty. The pressure in the air space 26 at the top of the receptacle 20 and overlying the body of liquid therein is atmospheric. As the tank 10 is being filled with water, the water will enter the bell mouth 25 and compress the air therein.

As shown in Fig. 2, the level of water in the tank 10 has, at this time, reached the level of the liquid in the receptacle 20, but the water has barely entered the lower end of the bell mouth 25, as shown by the level P''.

In the condition shown in Fig. 3, the level of the water in the tank 10 has reached H', which is equal to approximately twice the height of the liquid in chamber 26. As the water rises from the level H'' to the level H', the air in the bell mouth becomes compressed and the water rises therein. The pressure of the air serves to displace the level of the liquid in the capillary tube 24, and by the time the water level has reached H', substantially all of the liquid in the capillary tube 24 has been displaced. The water in the bell mouth has now reached a level P' shown in Fig. 3. Thereafter, as the level of water in tank 10 rises further, some of the compressed air is bubbled through the liquid in the chamber 20, and enters the space 26 and increases the air pressure over the body of liquid in the chamber 20 until the condition shown in Fig. 4 is reached. In this condition, the level of the liquid in the bell mouth 25 is as indicated at the level P, and the pressure over the body of liquid in the small chamber or small receptacle is superatmospheric and corresponds to the hydraulic head of the body of water 30 in the tank 10.

Thus, it will be seen from the above that the process of filling the tank 10 has stored potential energy within the receptacle 20 in the form of superatmospheric air pressure. When the valve 14 is opened, the water in tank 10 discharges at a rapid rate, with the consequence that the water level in the bell mouth 25 drops rapidly. The dropping of this water level in the bell mouth 25 is due to two causes. One is the rapid drop in the hydraulic head in the tank 10. The second cause is the flow of the water towards the outlet 12, which exerts suction in the bell mouth 25. As consequence, the pressure reduction within the bell mouth 25, together with the increased pressure in the space 26, causes the expulsion of a certain amount of liquid from the chamber 20. This liquid gets thoroughly mixed with the turbulent and still flowing body of water within

the tank 10, and is discharged therefrom with the stream of flowing water.

The expulsion of chemical from the receptacle 20 does not take place until after a large portion of the water of the tank 10 has already been discharged; the chemical, however, enters the larger chamber 10 when it is still approximately half-full of water. This is particularly desirable when this system is employed in connection with water closets when a very large amount of water is employed at each discharge. The chemical, however, enters the chamber 10, wherein the water is in a turbulent state, and gets thoroughly distributed through the body of water therein. As a result of this method of operation, the last portions of the water discharged by the tank 10 are always supplied with an adequate amount of chemical. Thus, the water which remains in the toilet receptacle 20 always contains some of the disinfectant.

At the end of the discharge of tank 10, the air pressure in the space 26 has again reached atmospheric, and as the tank 10 is filled with water, the operations described earlier are repeated.

The smaller receptacle 40 or 40' shown in Figs. 5 to 7 inclusive will be seen to operate upon the same principle as above described. It differs mainly from receptacle 20 in that it provides a filling opening and stopper therefor 41 in the top wall of the receptacle. An end wall of the receptacle 40 or 40' carries the small tube 24' and the bell mouth 25', which in this case are integral with each other and also integral with the end wall of the receptacle 40 or 40', making unnecessary the use of the cork or rubber 22. As shown in Fig. 7, the receptacle 40 may be attached to the outside of the tank 10 in any appropriate manner with the bell mouth 25' projecting into the interior of said tank. Further, the receptacle 40 may have an opening for filling, normally closed by a stopper 43, which if desired may engage the receptacle 40 by means of screw threads not shown.

The principles of the present invention may be readily employed to advantage by merely inserting the receptacle of Figs. 1 to 6, after it has been filled with the desired chemical or disinfectant, into the tank 10, and placing it on the bottom of the tank. Thus, the advantages of the present invention may be made available without any alterations whatever in the apparatus already installed. There is also the further advantage that the said receptacle may, at any time, be removed and refilled and again inserted into the tank 10, or it may be replaced by a similar receptacle which may be purchased already filled with the desired chemical or disinfectant.

Thus, by means of the present invention, householders or large building owners or operators may, by the mere purchase of the filled receptacles and their insertion into the tanks 10, provide an automatic supply of disinfectants to the toilet receptacles.

In other types of systems, the advantages of the present invention may be had by providing a receptacle carrying the chemical or disinfectant in larger quantities. In such systems the chemical or disinfectant container need not be small. The essential principle of operation, however, will be observed by combining the water receptacle tank and the chemical receptacle in such a manner that the mouth of the downwardly directed outlet of the chemical receptacle

is in communication with the interior of the water tank, and that the level of the water in the larger tank be normally substantially higher than the level of the chemical. It is also desirable in this type of system that the mouth of the outlet for the chemical should be disposed at a level somewhat above the level of the outlet of the water tank.

It will also be observed that the dosage of the chemical is dependent upon the difference in level between the normal high level of the water in the water tank and the level of the chemical in the small receptacle. In the present system, therefore, the relative dimensions of the two receptacles may be roughly as illustrated in the drawings. However, if it is desired to reduce the dosage, the receptacle 20 or 40 may be placed on a small support so that the difference between the two levels is thereby reduced.

I claim:

1. In combination, a first water receptacle having a discharge opening, a second receptacle supported by the first receptacle and substantially filled with a liquid desired to be introduced into the water in relatively small doses, a downwardly directed outlet attached to the upper part of said second receptacle, the outlet having downwardly and outwardly divergent walls terminating at a level near and above the bottom of the second receptacle, a tube connected to the inner end of said outlet and extending into the liquid and terminating near the bottom of the second receptacle, the lower end of said outlet being in communication with the interior of said first receptacle, means for filling said first receptacle with water to a level higher than the level of the liquid in the second receptacle, thereby forcing air through the outlet into the second receptacle and increasing the air pressure therein, and means for opening the discharge outlet of the water receptacle to discharge the

water therefrom and causing an increased air pressure in the second receptacle to expel into the first receptacle a small portion of its contents.

- 5 2. In combination, a water receptacle having a discharge opening, a chamber attached to a wall of the receptacle and exteriorly thereof near its bottom, said chamber being substantially filled with a liquid desired to be introduced into the water in the receptacle in relatively small doses, a downwardly directed outlet attached to the upper part of said chamber and passing through an opening in the wall of the receptacle into the interior thereof, the outlet having downwardly and outwardly divergent walls terminating at a level near and above the bottom of the receptacle, a tube connected to the inner end of said outlet, and extending into the liquid and terminating near the bottom of the chamber, means for filling said receptacle with water to a level higher than the level of the liquid in the chamber thereby forcing the air through the outlet into the chamber, and increasing the air pressure therein, and means for opening the discharge outlet of the receptacle to discharge the water therefrom and causing the increased air pressure in the chamber to expel into the receptacle a small portion of its contents.
